UNITED STATES PATENT OFFICE.

JOHN BROMET, FRANK THORMAN, AND HENRY CLAYTON WOOD, OF TADCASTER, ENGLAND.

APPARATUS FOR DRYING SEWAGE-SLUDGE AND THE LIKE.

1,153,192.

Specification of Letters Patent. Patented Sept. 14, 1915.

Application filed March 30, 1914. Serial No. 828,303.

To all whom it may concern:

Be it known that we, JOHN BROMET, FRANK THORMAN, and HENRY CLAYTON WOOD, subjects of the King of Great Britain and Ireland, residing at Tadcaster, in the county of York, England, have invented Apparatus for Drying Sewage-Sludge and the like, of which the following is a specification.

10 The object of our invention is to produce an apparatus that will economically, rapidly, and without nuisance, dry sewage sludge or other material containing water. To accomplish this object we employ one or 15 more rotating cylinders, heated both internally and externally, through which the material to be dried is caused to pass. During this passage the moisture in the material is evaporated and carried off by a current of 20 hot air circulated through the cylinder or cylinders by means of fans.

Description of drawings.—Figure 1 is a sectional elevation (on the line *a a* of Fig. 3) of a drying apparatus according to this 25 invention having two drying cylinders. Fig. 2 is a cross-sectional elevation of same (on the line *b b* of Fig. 3). Fig. 3 is a sectional plan of the same (on the line *c c* of Fig. 2).

30 According to our said invention, the wet sludge or other material to be dried is placed in the hopper A, whence it is continuously and automatically fed into the higher end of the upper cylinder B through a tube C, by 35 means of a worm D or other suitable appliance. The cylinders B and E are mounted on rollers F, and are continuously rotated by suitable gearing G. The cylinders are set on a slight slope, which causes the material within them to be carried forward 40 as they rotate, until it falls from the lower ends of the cylinders. A chute H is arranged to guide the material as it falls from the upper cylinder B into the end of the 45 cylinder E below it. The material is finally discharged in a dried state from the lower end of the bottom cylinder E, through the opening I in the air box J.

In the rotating cylinders are placed at intervals, as may be found advantageous, a series of scrapers, lifting vanes, and teeth, for breaking up the material. K is a fixed 50 scraper, which removes any material which may adhere to the interior surface of the cylinder, and throws it down to the bottom

again. As the material becomes drier, farther along the cylinder, pegs, or teeth L are fixed on the inside of the rotating cylinder, which will carry upward any large pieces of material that may be formed. 60 These pegs or teeth L pass between a number of pegs or knives M fastened to a fixed girder N, thus breaking up the material carried by the pegs or teeth L and throwing it down again to the bottom of the cylinder. 65 Farther still along the cylinder B, where the material has become so dry as to roll down easily into the bottom of the cylinder, and also in the lower cylinder E, vanes or lifting plates O are fixed to the interior surface of the cylinder. These, as the cylinders rotate, carry the material up toward the top and then drop it down through the current of 70 hot air.

The rotating cylinders are, except at the ends, surrounded by brickwork flues P, and are heated externally by the passing of hot gases of combustion from a furnace through these flues. At the same time the interiors 75 of the cylinders, and the material within them, are heated by hot air circulated through the cylinders by means of a fan.

An air-heater Q is provided for heating the air which circulates through the cylinders. The air flows around the series of tubes R and is heated by conduction from the furnace gases, which flow through the tubes R after issuing from the flues P surrounding the cylinders. The source of heat is preferably a high temperature destructor furnace S with large fire grate, fire brick, arch and lining, and closed ashpit, burning town's refuse, but coal or any other fuel may be used. 85

A circulating fan T maintains a steady 90 flow of air through the cylinders and air-heater in a circuit, so that the heated air is brought repeatedly into contact with the wet material and takes up the moisture from it, until the air becomes saturated or nearly so. The air is delivered from this fan T through the duct U and air-box J into the lower cylinder E. It passes along this cylinder and through the air-box V into and along the upper cylinder B. It leaves the upper cylinder through the air-box W, then passes along the duct X to the air-heater Q, and from thence it passes back through the duct Y to the suction inlet of the fan T. Or the circulation of the air through the cylinders 100

105 110

may be in the reverse direction if desired. A smaller fan Z is employed to draw off the saturated air from this circuit and discharge it into the chimney, the air thus drawn off 5 being replaced in the circuit by fresh air from the atmosphere, admitted through the opening I in the air-box J. The saturated air (moist and foul) is drawn off from the circuit by way of two ducts 10 1 and 2, which are the only outlets for the foul gases. The portion of the air passing through the duct 1 enters the ashpit 3 (which is otherwise closed) of the furnace S and is drawn through the grate, 15 thus providing the air for combustion of the material burnt in the furnace, and at the same time destroying the foul gases which may be evolved from the drying material in the cylinders and carried along with the 20 moist air. The other portion of the saturated (moist and foul) air, passing through the duct 2, enters the combustion chamber 4 of the furnace, or the flue 5 which is a continuation of the combustion chamber 4, 25 where it meets the flames and hot gases from the furnace, which effectually cremate any noxious fumes in the moist air. This admixture of moist air also serves to reduce the temperature of the furnace gases before 30 they come into contact with the plates of the drying cylinders.

Valves 11 and 12 are placed in the ducts 1 and 2, by means of which the amounts of air passing through the furnace, and directly 35 entering the combustion chamber, respectively, can be varied at will in accordance with the rate of combustion it is desired to maintain in the furnace. As an alternative arrangement, the duct U may be partly closed 40 by a valve 13 placed near its outlet into the air-box J, by which means a regulated amount of saturated (foul and moist) air may be forced through the duct 1 or 2, or 45 through both, thus assisting the action of the suction fan Z as described above.

The gases from the furnace and combustion chamber are drawn into the flues P surrounding the cylinders through the flue 5. After passing along the lengths of the cylinders they are drawn through the flue 6, 50 through the tubes R of the air-heater Q, and along the duct 7 to the suction inlet of the fan Z. This fan delivers the gases through the duct 8 into the chimney 9 and thence into the atmosphere.

Cleaning and inspection doors 10 are provided at suitable points, both for the cylinders and for the flues.

We have found by experience that it is 60 impossible to dry sewage sludge or similar material in a rotating cylinder without the fixed girder, scraper, pegs, etc., as described in this specification.

We claim:

1. In an apparatus for drying sewage

sludge or other material, the combination of a rotating cylinder or cylinders, externally and internally heated, and having a forced circulation of air through the interior, with a high temperature refuse destructor having 70 a large fire grate, fire brick arch and linings, a closed ashpit, a fan or other means for drawing foul air from the air circuit through the drying cylinders and forcing it into the ashpit and through the fire of the furnace 75 or into the combustion chamber, and valves for regulating the amounts of foul air forced through the fire of the furnace and discharged into the combustion chamber respectively, so as to reduce the air passing 80 through the fire to the minimum required for combustion, thus obtaining the most intense heat possible when burning fuel of low calorific value.

2. In an apparatus for drying sewage 85 sludge or other material and in combination, rotating cylinders adapted to receive the material to be dried, a fan, pipes connecting the cylinders and fan designed to form a circuit through which air is repeatedly circulated, furnace means for externally heating the cylinders adapted to subsequently heat, on the "regenerative principle", the air delivered to the cylinders, fan means for withdrawing a portion of the saturated and 90 four air from the said circuit and forcing it into the ashpit and combustion chamber of the furnace, and means for continuously replacing by fresh air the foul air drawn from the circuit.

3. In an apparatus for drying sewage sludge or other material and in combination, rotating cylinders adapted to receive the material to be dried, and through which a current of hot air is continuously circulated, 105 furnace means for heating the air, an ashpit under the grate closed to the atmospheric air, means for forcing the hot foul moist air drawn from the hot air circulating through the cylinders into the ashpit beneath the grate, and means for controlling the supply of foul air delivered to the ashpit to regulate the combustion of fuel in the furnace.

4. In an apparatus for drying sewage sludge or other material and in combination, 115 rotating drying cylinders, a fan, a furnace adapted to externally heat the rotating cylinders and provided with a closed ashpit, an air pipe extending between the suction inlet of the fan and the cylinders, pipes leading 120 from the delivery outlet of the fan into the closed ashpit and combustion chamber of the furnace, valves in the said pipes for regulating the amount of saturated air discharged into the ashpit and combustion chamber respectively, and means for introducing comparatively cool air into the combustion chamber to reduce the temperature of the furnace gases and prevent overheating 125 of the cylinders.

5. In a drying apparatus for drying sewage sludge or other material and in combination, rotating cylinders adapted to receive the material to be dried, a fixed internal
5 girder extending through one of the cylinders, a fixed scraper on the girder adapted to remove material adhering to the inner periphery of the cylinder, teeth mounted on the inner periphery of the cylinder, pegs attached to the girder adapted to co-act with

the teeth as the cylinder revolves, and means for continuously passing hot air through the cylinders to dry the pulverized material, substantially as described.
